UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

RAILWAY-CAR CONSTRUCTION.

Application filed May 18, 1925. Serial No. 31,144.

My invention relates to improvements in railway car construction and particularly to a novel method of forming car wall elements of railway cars.

5 An object of the invention is to construct the wall elements of railway cars in such a manner that portions thereof will be rigidified at the point of greatest strain by meaningless corrugations of great strength and 10 other portions of the said wall elements where the strain is not so great will be rigidified by the incorporation of embossments defining descriptive characters, indicia, symbols or designating markings 15 whereby the car may be readily identified and an advertising value derived from the use of such embossments.

Other objects of the invention will more clearly appear from the description herein- 20 after following.

In the drawings forming a part of this specification, Fig. 1 is an end elevational view of a box car having my improved construction incorporated therein. Fig. 2 is a 25 sectional view taken on a line corresponding substantially to line 2—2 of Fig. 1. Fig. 3 is a side elevational view of the side door of a railway box car embodying my improved car construction. Fig. 4 is a sec- 30 tional view taken on a line corresponding substantially to line 4—4 of Fig. 3.

Referring first to the construction shown in Figs. 1 and 2, I have shown my improvements as applied to the end wall of a box car. In said drawings the end wall is shown as composed of upper and lower panels designated broadly as A and B respectively. Each of said panels is flanged at the respective side vertical margins as indicated 40 at 10—10, said flanges preferably constituting the corner posts of the car and forming a suitable rigidifying means whereby the end wall is suitably attached to the corresponding side walls of the car. The lower 45 margin of the end wall is suitably rigidified by a beam 11, preferably of angle shape, which extends horizontally between the side walls of the car and adjacent its upper margin the end wall is rigidified by a horizontally extending beam 12, preferably 50 formed of Z-shaped section. The lower panel B has embossed therein a plurality of horizontally extending contiguous cor-

rugations 13 which serve to resist bulging of the end wall intermediate the vertical margins thereof. The upper panel A slightly overlaps the lower panel B and the parts are united adjacent the upper corrugation of said panel B by means of a row of rivets as indicated at 14, and each of the vertical flanged margins 10 at the sides of the upper panel A is crimped over the corresponding vertical marginal flange of the lower panel B for the purpose of presenting a flush surface on the inner face of the said flange 10 where the side wall of the car is normally disposed. Said upper panel A carries a descriptive symbol 15, which is preferably formed by embossing a portion of the plate to form a rigidifying means adapted to reinforce the panel against bending on various cross-lines. Said designating symbol 15 is preferably characteristic of a railway trade mark and serves as a perpetual designating mark in addition to providing great strength and rigidity in the wall parts. The symbol 15 in the particular application illustrated herein includes a border having horizontally extending corrugations 16—16 and vertical corrugations 17—17 and the body of the plate intermediate the border is rigidified against buckling by the inclusion of letters as indicated at 18. The usual wooden sheathing within the car is indicated at 19, said sheathing being preferably spaced from the metallic panels by means of battens as indicated at 20 and 21 respectively.

Referring now to the construction shown in Figs. 3 and 4, I have shown my improvements as applied to the side door of a car, the framework of the door being indicated by vertical marginal members 110—110, upper horizontal marginal member 111 and lower marginal member 112. The main body of the door includes lower and upper panels as indicated at C and D respectively. Said lower panel C is secured to the vertical margins 110—110 as indicated at 113 and to the lower horizontal margin 112 as indicated at 114. The body of the panel is rigidified by a series of horizontal corrugations 115 embossed in the plate and which extend between the vertical members 110—110. The upper panel D is secured to the respective vertical margins 110 as indicated at 116 and to the lower panel and to the upper hori-

horizontal marginal member 111 as indicated at 117 and 118 respectively. Said panel D has embossed therein the descriptive symbol 119 which is formed to resist bending of the 5 plate on various cross-lines.

The two embodiments of my invention as 10 illustrated herewith are typical examples of preferred construction for the vertical wall elements of railway cars and while I have shown the symbol in the upper portion of the panel, this arrangement may be modified in any suitable manner. The disposition of the corrugations at the lower portion of the 15 panelling is a preferred arrangement inasmuch as the tendency to bulge is generally greater at the lower part of the car wall than at the top thereof and the series of horizontally extending corrugations provide for great strength intermediate the vertical 20 margins of a panel and it is also desirable, in order to secure sharpness of definition in the parts of the symbol, that the plate in which said symbol is embossed be as thin as the strain on the car wall will consistently permit. Consequently the use of horizontal corrugations at the lower portion of the panel and the symbol at the upper portion thereof permits the use of a lighter plate for the upper portion of a panel. 25

30 Although I have shown and described a preferred manner of carrying out my invention, the same is merely illustrative and I contemplate all changes and modifications that come within the scope of the claims 35 appended hereto.

What I claim is:

1. In a car wall element including a panel 40 of sheet metal, said panel being strengthened within its margins by embossments defining intelligible indicatory characters and a rectangular embossment disposed outwardly of said first named embossments, said rectangular embossment being disposed inwardly of the edges of the sheets and 45 provided with extensions adapted to continue the reinforcement beyond the main portion of said rectangular embossment.

2. In a car wall element the combination 50 of a panel of sheet metal, said panel being strengthened within its margins by embossments defining intelligible indicatory characters and a rectangular embossment disposed outwardly of said first named embossments, said rectangular embossment being 55 disposed inwardly of the edges of the sheets and provided with extensions adapted to continue the reinforcement beyond the main portion of said rectangular embossment, said extensions decreasing in width and

depth as the margin of the panel is approached.

3. In a railway car wall element the combination with vertical marginal reinforcing members, of a body section formed of metallic plate extending between said margins, the body of said plate being reinforced by intelligence conveying symbols embossed therein, an embossed continuous rectilinear outline surrounding said symbol, said outline being disposed an appreciable distance 65 from the margin of said element, and integral embossments extending outwardly from the corners towards the margins to reinforce the plate intermediate the margins and the continuous outline.

4. In a railway car element, the combination of a main body portion formed of sheet metal, said element being formed with a plurality of corrugations extending intermediate the vertical margins to reinforce the 80 plate intermediate said margins, said corrugations being spaced apart an appreciable distance and having other corrugations embossed thereon disposed substantially at right angles to the first named corrugations but spaced inwardly from the ends thereof; said vertical and horizontal corrugations together presenting the appearance of a 85 rectangular framework and intelligence conveying characters embossed out of the main body of the plate for the purpose of reinforcing the said plate intermediate the panel.

5. In a car wall, the combination with 90 horizontally extending beams disposed respectively at the upper and lower margins thereof; of vertically extending reinforcing marginal flanges formed on the wall and extending substantially between said upper and lower margins, a plurality of substantially horizontally extending corrugations 100 in the lower portion of the car wall and constituting beams extending between the respective vertical margins; and rigidifying means adapted to rigidify the upper portion 105 intermediate said lower portion and top margin of the car wall, said means including an embossment representing a rectangular framework forming horizontally and vertically extending beams and intelligible 110 indicatory characters embossed within the said framework to strengthen the plate intermediate the framework.

In witness that I claim the foregoing I have hereunto subscribed my name this 15th 115 day of May, 1925.

ARGYLE CAMPBELL.
